TIRE STUDDING DEVICE

Robert W. Houston, Cincinnati, Ohio, assignor to
Studebaker Corporation, South Bend, Ind.

Filed Apr. 25, 1967, Ser. No. 6,824

Term of patent 14 years

(Cl. D54—13)

FIG.1

FIG.3

FIG.2

FIG.4

FIGURE 1 is a perspective view of a tire studding device showing my new design, and particularly showing the front end thereof;

FIGURE 2 is one side view of my tire studding device, the opposite side view being substantially the same;

FIGURE 3 is a top plan view of my tire studding device; and

FIGURE 4 is a rear end view thereof.

I claim:

The ornamental design for a tire studding device, substantially as shown and described.
